UNITED STATES PATENT OFFICE.

DANIEL SCHNEIDER, OF LODI, CALIFORNIA.

AUTOMATIC RAILROAD-CROSSING GATE AND SIGNAL.

Application filed April 21, 1927. Serial No. 185,520.

This invention relates to certain new and useful improvements in automatic railroad crossing gates and signals, and has more particular reference to an improved protective device of this character adapted to be employed at grade crossings where highways intersect railroads.

The primary object of this invention is to provide a device of the above kind involving a normally lowered or closed gate adapted to extend across the highway at the crossing so as to warn the drivers of vehicles of their approach to the crossing, and means for automatically opening the gate as the vehicle approaches the same including a depressible ramp or platform over which the vehicle must travel in passing the gate.

A more specific object of the invention is to provide simple and effective means for raising the gate to open position including a depressible ramp or platform arranged at the approach side of the gate and operatively connected to the latter.

A further object is to provide simple and effective means for sounding an audible signal or alarm upon depression of the ramp and opening of the gate so that additional assurance is had of warning the driver of the vehicle of his approach to the crossing immediately before passing onto the track rails of the railroad.

Other objects will become apparent as the nature of the invention is better understood, and the same consists in the novel form, combination and arrangement of parts herein-after more fully described, shown in the accompanying drawings and claimed.

In the drawing, wherein like reference characters indicate corresponding parts throughout the several views,

Figure 1 is a somewhat diagrammatic fragmentary top plan view showing automatic railway gates and signals, constructed in accordance with the present invention, operationally arranged on the highway at opposite sides of the railroad track;

Figure 2 is an enlarged fragmentary side elevational view of one of the gates and signals shown in Figure 1 together with the associated actuating mechanism;

Figure 3 is a fragmentary view partly in top plan and partly in longitudinal section, of the device shown in Figure 2, with parts removed and omitted to reveal details of construction;

Figure 4 is a transverse section taken substantially upon line 4-4 of Figure 1; and

Figure 5 is a fragmentary view partly in elevation and partly in vertical section, showing the bell of the signal and means for actuating the hammer thereof as arranged when the gate is initiating its lowering movement.

Referring more in detail to the drawings, automatic gates and signals constructed in accordance with the present invention are adapted to be disposed or arranged at opposite sides of the highway 5 and at opposite sides of the track 6 of the railroad which said highway intersects for respectively controlling traffic moving in opposite directions, as shown in Figure 1, and as the construction of each automatic gate and signal is the same, description of one will suffice for both.

As shown, each automatic gate and signal embodies a suitable post 7 rigidly mounted centrally between the sides of the highway and at a point adjacent one side of the railroad, and pivotally mounted at its inner end as at 8 upon the post 7 is a vertically swinging gate or gate bar 9 adapted, when lowered to closed position, to extend across half the road or highway 5 as shown in Figures 1 and 4 to control the traffic approaching the track in one direction, a suitable post 10 being rigidly mounted at the adjacent outer side of the road or highway to form a rest or support for the free outer end of the gate when lowered.

Embedded in the roadway coextensive with the latter as well as arranged at the approach side of the gate at the same side of the highway and the railroad is a rectangular elongated frame 12 of a vertically swinging ramp which further includes floor member 13 suitably secured upon and covering the ramp frame 12 and preferably formed of sheet metal. The outer end of the ramp frame is pivoted to the outer end of the base frame 11 upon a transverse pivot rod 14 whose ends are fixed in the side members of the base frame 11. It will thus be seen that the free end of the ramp extends to a point adjacent the associated gate 9, and the floor 13 of the ramp is extended beyond the free end of the ramp frame 12 as well as inclined downwardly so that the wheels of a vehicle may readily ride off of the ramp in passing the gate.

Rigid with the pivoted end of the gate 9 is a pulley segment 15 over which passes a flexible member 16 having one end attached to

the pulley segment and its other end attached to the adjacent free end of an actuating bar 17 fixed to the adjacent side of the ramp frame as at 18. As shown clearly in Figure 3, the actuating bar 17 is fastened to the ramp frame at its outer end, and is directed laterally and so as to terminate at a point directly below the pulley segment 15 for connection with the flexible member 16. It is thus apparent that when the left hand wheels of a vehicle ride onto the ramp it will be automatically depressed by the weight of the vehicle so as to exert a downward pull on the flexible element 16, causing the latter to unwind from the pulley segment 15, and thereby causing the gate 9 to swing upwardly to open position as indicated by dotted lines in Figure 6. Thus, the vehicle effects opening of the gate when approaching the latter before the vehicle may pass over the railroad track. A suitable means is provided for normally yieldingly lowering and maintaining the gate lowered with the ramp in raised inclined position and the flexible element 16 wound upon the pulley segment 15. For this purpose a helical tension spring 19 is preferably attached at its upper end to the gate inwardly of the post 7, and at its lower end to an anchor 19^a, thereby insuring lowering and closing of the gate as soon as the vehicle passes off of the ramp. A suitable reflector element 20 is preferably fastened to the approach side of the gate 9 intermediate the ends of the latter so that the lights of a motor vehicle may shine thereon when the vehicle approaches the railroad, thereby furnishing additional effective warning of the approach to the crossing at night time. Obviously, suitable train controlled means may be provided for preventing depression of the ramp or platform of the device arranged at each side of the railroad so that the gate may not be opened when a train is approaching the crossing. However, as such train controlled means are broadly old and well known in the art, specific disclosure thereof herein is not made, the same forming no specific part of the present invention.

It will be noted that the gate 9 is pivoted to the post 7 at a point below the upper end of the latter, and suitably mounted upon the upper end of said post 7 is the sound producing shell 21 of a bell forming part of an audible signal. This signal bell further embodies a pivoted hammer 22 mounted upon a horizontal axis at its lower end and normally yieldingly urged into contact with the shell at its striking upper end as at 23. The hammer 22 is provided with a lateral lug 24 intermediate its ends and above its pivot 25, and mounted upon the pivot 25 intermediate its ends is a lever 26 which is weighted at its lower end as at 27 so as to normally assume a vertical position with its upper end in engagement with the lug 24 as shown in Figure 4. The lower

end portion or arm of the lever 26 is also formed with a lateral lug 28, and projecting from one side or flange of the pulley segment 15 radially of and concentric with the gate pivot 8 are a plurality of teeth or prongs 29 in the path of which the lug 28 is arranged. The teeth 29 are so disposed as to pass inwardly of the lug 28 as shown by full lines in Figure 4 when the gate is lowered, the same freely ratcheting pass the lever 26 without influencing the hammer 22 when the gate is so lowered. However, it will be seen that upon raising the gate the teeth 29 will successively engage the lug 28 so as to cause the hammer 22 to be rapidly vibrated for causing a plurality of taps upon the sound producing shell 21, thereby additionally warning a driver of a vehicle of his final approach to the railroad track as the gate is opened. While the bell mechanism has been specifically shown and described as associated with the gate post, it is nevertheless obvious that the same may be associated with a separate post provided a second segment is mounted upon the latter post and provided with the teeth 29 as well as operatively connected to the platform of the device, the hammer 22 and lever 26 being also mounted on this additional post. In other words, it is not desired to limit the invention to mounting the alarm mechanism upon the gate post as shown and described.

In operation, the left hand wheels of a vehicle approaching the crossing from either side of Figure 1 will ride onto a ramp or platform, thereby depressing the ramp and swinging the associated gate 9 upwardly to open position. Complete passage of the vehicle past the gate is insured before closing of said gate by riding of the vehicle wheels on the extended free end of the platform floor, and as the vehicle rides off of the platform and onto the railroad track, the spring 19 will return the parts to normal position with the ramp raised and the gate 9 closed for the succeeding actuation. In each instance, the opening of the gate will effect sounding of the bell as described above, thereby insuring proper caution in approaching and passing over the tracks. Of course, if automatic locking means is provided for prevent depression of the platforms and openings of the gates upon approaching of a train toward the crossing, the gates will not be opened and the vehicle will stop until passing of the train, whereupon automatic release of the platform will insure that opening of the gate will subsequently take place due to the weight of the vehicle upon the platform in question. It is noted that reflector elements such as employed at 20 are in general use in fixed positions upon roadways at the present time, and reflector elements are quite conspicuous in the day time as well as at night. By mounting such a reflector element upon the

intermediate portion of the gate vision there-
of is more effectively insured than when the
same are mounted at the side of the roadway
as is now practiced. Moreover, reflection of
the light from the headlights of approaching
5 vehicles is more effectively insured by this
arrangement, thereby providing effective
cautioning means for service at night time.

From the foregoing description it will be
10 seen that I have provided a simple and effective
crossing gate and signal mechanism
which may be readily installed and is com-
paratively inexpensive in character.

Minor changes may be made without de-
15 parting from the spirit and scope of the in-
vention as claimed.

What I claim as new is:—

1. In a railroad highway crossing gate, a
post at one side of the railroad tracks and at
20 the center of the highway, a gate bar pivoted
at its inner end on the post for vertical swing-
ing movement and adapted to be lowered to
closed position extending half way across the
highway, a hinged depressible platform
25 ramp in the highway adjacent and at the
approach side of the gate and having a free
exit end, means operatively connecting the
free end of the ramp to the gate for opening
the latter upon depression of the ramp, yield-

able means to normally lower the gate and 30
raise the ramp, said connecting means em-
bodying an inwardly projecting bar rigid
with the free end of the ramp, a pulley ele-
ment on the pivoted end of the gate, and a
flexible member attached to and passed over 35
the pulley element and having its lower end
attached to the bar and the yieldable means
comprising a spring attached at one end to
the pulley element and ground anchored at
its other end. 40

2. In a railroad highway crossing gate, a
post at one side of the railroad tracks and
at the center of the highway, a gate bar pivoted
45 at one end on the post for vertical swing-
ing movement and adapted to be lowered to
closed position extending half way across the
highway, a hinged depressible platform
ramp in the highway adjacent and at the
50 approach side of the gate and having a free
exit end, an arm projecting from the free
swinging end of the ramp, a pulley element
on the pivoted end of the gate bar, a cable
anchored to the pulley and attached to the
55 arm, and a spring connecting the pulley to
the ground at the side thereof opposite the
cable connection with the arm.

In testimony whereof I affix my signature.
DANIEL SCHNEIDER.
